UNITED STATES PATENT OFFICE.

NELSON O. WILCOX, OF OMAHA, NEBRASKA.

IMPROVEMENT IN BED-BOTTOMS.

Specification forming part of Letters Patent No. **138,971**, dated May 13, 1873; application filed April 19, 1873.

To all whom it may concern:

Be it known that I, NELSON O. WILCOX, of Omaha, in the county of Douglas and State of Nebraska, have invented a new and useful Improvement in Elastic Bed-Bottoms, of which the following is a specification:

The object of this invention is to simplify, cheapen, and, at the same time, improve spring bed-bottoms; and it consists in the construction and the arrangement and combination of parts hereinafter described.

In the accompanying drawing, Figure 1 represents a plan view of a bedstead with my improved bottom thereon. Fig. 2 is a vertical longitudinal section of Fig. 1 taken on the line *xx*. Fig. 3 is a modification of Fig. 2. Fig. 4 is a cross-section of Fig. 2 on the line *yy*. Fig. 5 is a cross-section of Fig. 3 on the line *zz*.

Similar letters of reference indicate corresponding parts.

A represents the bedstead. *B B* are the cleats at the ends of the bedstead, upon which the spring slats are supported. *C* represents the spring slats; *D*, the middle slats. *E* are cross-pieces which rest on the spring slats and support the middle slats, as seen in Fig. 2. The spring slat is made in three pieces, *F* and *G*, with a supporting slat, *H*, beneath. The pieces *H* are connected with the parts *FG* by

means of elastic bands I made of rubber or equivalent material. The cross-pieces *E* are notched onto the spring slats *C*, as seen at *J*, and the middle slats *D* are notched onto the cross-piece, as seen at *K*.

In the middle of the spring slat a single broad band, as seen in Fig. 3, may be used, attached to the under slat *H*, as is indicated in the drawing; but I prefer the arrangement shown in Fig. 2, where two elastic bands are employed. The spring slats *C* are placed next the sides of the bedstead, as seen in Fig. 1, and with this arrangement of the parts the middle or intermediate slats *D* are made to partake of the elasticity of the spring slats, and the whole to form a highly elastic and durable bed-bottom, without the use of metallic springs or metallic fastenings. This bed-bottom is easily made, and is simple and cheap.

Having thus described my invention, I claim as new and desire to secure by Letters Patent—

The arrangement and combination of the spring slats *C*, middle slats *D*, and cross-piece *E*, as and for the purposes described.

NELSON O. WILCOX.
